UNITED STATES PATENT OFFICE.

HIRAM H. SPONENBURG, OF WADSWORTH, ILLINOIS, ASSIGNOR OF
ONE-HALF TO EDWARD LAAS, OF OTTUMWA, IOWA.

RAILWAY-RAIL STAY.

SPECIFICATION forming part of Letters Patent No. 779,104, dated January 3, 1905.

Application filed September 17, 1904. Serial No. 224,796.

To all whom it may concern:

Be it known that I, HIRAM H. SPONENBURG, of Wadsworth, in the county of Lake, in the State of Illinois, have invented new and useful Improvements in Railway-Rail Stays, of which the following, taken in connection with the accompanying drawings, is a full, clear, and exact description.

This invention relates to devices applied to the rails of railways for the purpose of preventing longitudinal creeping of said rails.

The object of the invention is to provide a rail-staying device which shall be readily applied to the rail and efficient in resisting the aforesaid creeping of the rail and simple and inexpensive in construction; and to that end the invention consists in the novel construction of the rail-stay hereinafter described and claimed.

In the annexed drawings, Figure 1 is a transverse section of the rail provided with my improved rail-stay. Fig. 2 is a plan view of the same, indicating by an arrow the direction in which the rail tends to creep. Fig. 3 is a transverse section on line *xx* in Fig. 2. Fig. 4 is a detached plan view of the strap or bar by means of which the rail-gripping jaws are held in engagement with the rail, and Fig. 5 is an inner face view of the separately-formed rail-gripping jaw.

Similar letters of reference indicate corresponding parts.

R represents the railway-rail, and A the cross-tie which supports the said rail.

b and *c* denote the rail-gripping jaws of the rail-stay. The jaw *b* is formed directly on one of the ends of the strap or bar *d*, which extends across the under side of the rail R, and is formed with a screw-threaded cylindrical end portion *e*, which extends beyond the edge of the rail. The jaw *c* consists of a block which is formed with a groove *c'*, shaped to receive and grip the edge of the rail. Below this groove is an orifice *f*, extending transversely through the block and receiving through it the screw-threaded end portion *e* of the strap *d*. A nut *g*, applied to said end portion and engaging the outer face of the block, serves to tighten the grip of the two

jaws on the rail. To obtain a more secure hold on the rail, I form the groove *c'* with serrations, as shown at *c''* in Fig. 5 of the drawings, which serrations become embedded in the edge of the rail when the nut *g* is thoroughly tightened on the end portion *e* of the strap *d*.

The end portion *e*, which is an extension of the strap *d*, is disposed at an angle to the main portion of said strap, as shown in Fig. 4 of the drawings. This construction causes the jaw *b* to be held normally out of contact with the side of the cross-tie, while the base of the jaw *c* bears on the side of said cross-tie. The result is that when the rail R is subjected to severe end pressure the jaw *b* is forced toward the cross-tie and causes the front edge of said jaw to bite the edge of the rail, and thus obtain a firmer grip thereon. To allow the jaw *b* to move as aforesaid without disturbing the grip of the jaw *c*, I taper the side edges of the strap, as shown at *l*, to the strap extension *e* and widen the orifice *f* toward its inner end and form the base of the jaw *c* with a recess *f'*, which is flared from the inner end of the orifice *f*, so as to allow the strap *d* a limited lateral movement.

The block, which is formed with the rail-gripping groove *c'*, has depending from it an integral flange *h*, which bears on the side of the cross-tie to resist the creeping of the rail. A web *i* extends from the block to the bottom of the flange *h* to brace said flange.

What I claim as my invention is—

1. A rail-stay consisting of a strap disposed transversely under the rail, a rail-gripping jaw on one end of said strap, and a block connected to the opposite end of the strap adjustable toward and from the aforesaid jaw and provided with a groove engaging the flange of the rail and with a flange engaging the side of the cross-tie.

2. The improved rail-stay consisting of a strap disposed transversely under the rail and formed at one end with a rail-gripping jaw and at the opposite end with a screw-threaded extension, a block formed with a rail-gripping groove, an aperture below said groove receiving through it the aforesaid extension

of the strap, a depending flange engaging the cross-tie, and a nut on said strap extension as set forth.

3. A rail-stay consisting of a strap disposed transversely under the rail and formed at one end with an integral rail-gripping jaw and at the opposite end with a tapered portion terminating in a screw-threaded extension disposed at an angle to the strap, a block formed with a rail-gripping groove, an aperture below said groove receiving the strap extension,

a flaring recess at the inner end of the aperture receiving the tapered portion of the strap, a flange depending from the block and bearing on the side of the cross-tie, and a nut on the strap extension all constructed and combined in the manner set forth. 15
